Atlys.

UNITED STATES PATENT OFFICE.

LAWRENCE L. MILLER, OF BROCKTON, MASSACHUSETTS, ASSIGNOR TO OSCAR L. REDIFER, OF PHILADELPHIA, PENNSYLVANIA.

BOTTOM-FILLING MACHINE.

Application filed December 5, 1921. Serial No. 519,901.

To all whom it may concern:

Be it known that I, LAWRENCE L. MILLER, a citizen of the United States, residing at Brockton, in the county of Plymouth and 5 State of Massachusetts, have invented certain new and useful Improvements in Bottom-Filling Machines, of which the following is a specification.

This invention relates to machines where- 10 by an operator is enabled to conveniently and rapidly apply to the outer face of the inner sole of a shoe, before the application of the outer sole, the usual layer of bottom filler, said layer being formed by the opera- 15 tor, by the aid of the machine, and inter- posed, in the completed shoe, between the inner and outer soles.

The filler is composed of a mixture, usually including ground cork and a viscid 20 binder which is rendered plastic by heat supplied to the machine. The filler while hot and plastic, is applied by a heated knife manipulated by the operator, and is compacted and spread by a heated spreading 25 member.

The machine includes a knife-holder and heating means, whereby the pot, the knife- 30 holder, and the spreading member, are heated, the heated knife being first used to trans- 35 fer the plastic filler from the pot to an inner sole, and fashion the filler into a rough layer, after which the layer is compacted and smoothly surfaced by the spreading member.

The object of the invention is to provide a 40 machine adapted for the convenient con- joint use of two operators, standing at op- posite sides of the machine.

The invention is embodied in the improve- 45 ments hereinafter described and claimed.

Of the accompanying drawings forming a part of this specification,—

Figures 1 and 2 are perspective views, 45 showing different embodiments of the invention.

Figure 3 is a wiring diagram.

Figure 4 is a transverse section of one of the knife-holders.

The same reference characters indicate 50 the same parts in all of the figures.

In the drawings, 12 represents an oblong 55 pot constituting an element of my improved machine, and supported in a horizontal po- sition by legs 13. The longer sides of the

provided at opposite sides of the machine, for two operators, each facing one of said longer sides, one standing relatively near one end of the pot, the other standing near the opposite end. Above the pot are two 60 groups of machine elements, each group including a holder 14 for the usual manually operated filler-applying knives or spatulas 15, and a spreading member 16, whereby a layer of filler, roughly formed on an inner 65 sole by a knife 15, may be spread, compacted, and smoothly surfaced, when rubbed across said member by the operator.

The holder 14 is preferably a cylindrical metal block having slots or pockets 160, 70 formed to receive the major portions of the knife blades. The spreading member 16 is preferably a cylindrical metal roll coaxial with the holder. One of said groups is located over one end portion of the pot, and 75 the other over the opposite end portion, the major axis of the two groups being in alignment with each other, and in the same vertical plane with the major axis of the pot, so that the said groups are centrally located 80 over the pot, and are substantially parallel with, and equidistant from the longer sides thereof.

The machine includes heating apparatus, 85 adapted to heat the pot and the said groups. Said apparatus as shown by Figure 1, in- cludes two electrical heating units 18, in- serted in sockets 19 formed on the pot, and two similar units 20, inserted in sockets formed in the alined knife-holders 14, and 90 spreading members 16. The units 18 are adapted to heat the pot sufficiently to melt the fusible ingredients of the filler in the pot.

The units 20 are adapted to suitably heat 95 the knife-holders 14, and the surfaces of the spreading members 16. In this embodiment of the invention the heating apparatus in- cludes two independent divisions. One divi- 100 sion is operatively related to one end por- tion of the pot, and the group of elements above that end. The other division is oper- atively related to the opposite end of the pot, and to the other group of elements. Each of said divisions includes a heating 105 unit 18, a heating unit 20, and suitable conducting wires 22 and 23. The circuit which includes the units 18 is controlled by switches 24, in a switch-box 25. The circuit which includes the unit 20 is controlled by 110

a switch 26 in said box. The switch-box and the said groups are supported by a frame 27, mounted on the pot, and preferably composed of metal tubes, through portions of which portions of some of the conducting wires pass, said frame including branch members, connected with and supporting the aligned knife-holders and spreading members.

10 The switch-box is preferably provided with two switches 24, and two switches 26, as indicated by full and dotted lines in Figure 1, and diagrammatically by Figure 3, there being a switch 24 and a switch 26 at 15 each side of the switch-box, the arrangement being such that one of the divisions of the heating apparatus is controlled by one operator, and the other division by the other operator. Each operator is, therefore, enabled to work independently of the other.

15 A supply of filler may be stored in the central portion of the pot, or midway between its ends, and moved therefrom by each operator to his end of the pot, as occasion requires.

20 The heating medium may be steam supplied by a pipe 30 (Figure 2), and suitable branch pipes 31 and 32, to a steam jacket 12^a associated with the pot, and to the groups composed of the elements 14 and 16, 25 portions of the branch pipes 32 passing through the tubular elements 14 and 16. A valve may be provided at 34, whereby the supply of steam may be controlled. A drain pipe 35 may be provided for conducting away the water of condensation and vapor.

25 It will now be seen that I have provided a

machine adapted to occupy a small space in a shoe factory, and to permit two operators 40 to conveniently perform the bottom filling operation, each working independently of the other.

I claim:

1. A bottom-filling machine, comprising 45 an oblong pot, means for supporting the same horizontally with its longer sides unobstructed, so that stations are provided for two operators, standing one at one side, and the other at the opposite side, of the 50 pot, each facing one of said longer sides, two groups of machine elements supported above the pot in axial alinement with each other, and substantially parallel with, and equidistant from the longer sides of the 55 pot, each group including a filler-applying knife-holder, and a filler-spreading member, one group being arranged over one end portion of the pot for use by one of the operators, and the other group over the opposite end portion, for use by the other operator, and heating apparatus adapted to heat the pot and the said groups.

2. A bottom-filling machine substantially 65 as specified by claim 1, said heating apparatus including two independent divisions, one operatively related to one end portion of the pot and the group thereabove, and the other to the opposite end of the pot and the corresponding group, means being provided for 70 the control of one of said divisions by one operator, and of the other division by the other operator.

In testimony whereof I have affixed my signature.

LAWRENCE L. MILLER.
